UNITED STATES PATENT OFFICE.

CHARLES PARHAM, OF PHILADELPHIA, PENNSYLVANIA.

CAR-SEAT LOCK.

SPECIFICATION forming part of Letters Patent No. 372,430, dated November 1, 1887.

Application filed July 23, 1887. Serial No. 245,492. (No model.)

To all whom it may concern:

Be it known that I, CHARLES PARHAM, a citizen of the United States, residing in the city and county of Philadelphia, in the State 5 of Pennsylvania, have invented an Improvement in Car Seat Locks, of which the following is a specification.

My invention relates generally to such seats as are constructed with shifting or reversible backs, and particularly to the locking device by which the car seat back and its arm are locked together in given adjustments, as well as to means for the prevention of the picking of the lock by which the back arm is locked 15 to the seat.

The object of my invention is to provide an automatic locking device, adjustably connected with the back, or with the back arm, and adapted, by gravity, to fall into a slot or stop 20 on one of said parts or members and to thus lock said parts together,—and its further object is to provide a device by which the introduction of knife blades and similar articles between the outer surface of the back arm and 25 the inner surface of the seat arm, will be rendered impossible, and the shifting of the spring controlled lock bolt, by which said parts are locked together, be prevented.

In the accompanying drawings Figure 1 is a 30 side elevation of the end of a car seat, of the back arm, and of the operative parts of the lock by which said back and back arm are locked together, the position of said parts, when the back is shifted to the other side of 35 the seat, being shown in dotted lines. Fig. 2 is an end elevation, partly in section through the seat arm, the back arm and its bolt slots, and the seat arm bracket, of part of the devices shown in Fig. 1. Figs. 3, 4, 5, and 6, 40 are detail views in perspective of the parts of the locking device shown in Fig. 1.

Similar letters of reference indicate corresponding parts.

In the drawings A is the seat arm, B the 45 back arm at one end pivotally attached thereto, and, at the other end, by a hinged joint, connected with the back plate C. The back plate C is provided with a disk portion D part of the periphery of which has a wall E within 50 which the ring J, in which the arm B terminates, is housed; on this ring the back plate C,

by reason of the space between the ends of the wall E, may, through a limited path, be rocked.

The disk D is provided with projections F 55 and G G' between which the ends M and N respectively of a bolt L are adjustably contained. The ring J is provided with slots or stops K K', each so located as that when the lower end of the wall E of the back plate C is 60 revolved into contact with the edge of the back arm B, the lower of said slots is in position to permit the lower end of the bolt L to drop into it. When the back arm is unlocked from the seat arm, and the back arm and back 65 carried to the other side of the seat, and the back revolved to a new position of adjustment in respect to the seat, the bolt L, by gravity, 70 drops, the end N thereof withdrawing from the slot K' and the end M falling into the slot K, the back and back arm being thereby locked together in their new positions of adjustment.

O is a plate, at one side provided with a pin P adapted to take into a hole H in the disk D and provided with screw holes through which 75 it may, by screws taking into holes f g, be secured over the parts of the locking device.

I is a slot in the periphery of the ring J to permit of the passage of the pin P in the adjustment of the back and back arm in respect 80 to each other.

The back arm B is supported in the usual manner by taking into a bracket Y attached to the inside of the car seat frame. It is locked to the car seat by a lock of usual construction 85 consisting of a retractable bolt V, controlled by a spring X, and adapted to be operated to be withdrawn from its seat, in the outer side of the back arm, by a key U.

In locks of this class, as heretofore constructed, it has been possible to unlock the lock by inserting the blade of a knife, a sheet of metal, or a kindred article, between the face of the back arm in which the bolt slot was located, and the face of the bracket lying in 95 contact therewith, with the result that the knife blade, or sheet of metal, acting downwardly upon the beveled end of the lock bolt forced said bolt out of its seat in the back arm, and thus permitted the back to be thrown to 100 the other side of the seat.

In my device I provide two bolt slots Q R,

one to receive the locking bolt when the back arm is at one side of the seat, and the other to receive it when the back arm is at the other side of the seat. These bolt slots are separated by a wall or rib S which projects beyond the surface of the back arm, and which, when the back arm is in the bracket Y, is in place immediately over a shoulder T formed upon the inner surface of said bracket at a point above the hole therein through which the bolt lock enters.

It is obvious that this construction prevents the introduction of a knife blade, or similar article, to and in contact with the bolt and the 15 unlocking of said lock.

Having thus described my invention, I claim:

1. In combination, a car seat back, back arms connected by a hinged joint with the back, 20 a locking device adjustably attached to one of said members, and adapted, by gravity, to drop into a slot or stop in the other member and lock said members together, as specified.

2. In combination, a car seat back, back 25 arms connected by a hinged joint with the back,

and a locking device adjustably attached to one of said members and adapted, by gravity, to drop into a slot or stop in the other member and lock said members together, and, by gravity, when the back is shifted to the other side of said seat, to drop out of said slot or stop and permit the back to be adjusted at a new angle to the seat, and then, by gravity, to drop into a second slot and lock said members together, as specified. 30

3. In combination, a car seat back arm provided with two bolt slots and a rib or wall which projects outwardly beyond the face of said arm, and separates said slots, a locking bolt operating in connection with said bolt 40 slots, and a bracket attached to the seat and having, on its face adjacent to the back arm, a rib, as specified.

In testimony whereof I have hereunto signed my name this 23d day of July, A. D. 1887.

CHAS. PARHAM.

In presence of—

J. BONSALL TAYLOR,
F. NORMAN DIXON.
